US00D679357S

(12) **United States Design Patent**
Wright et al.

(10) **Patent No.:** **US D679,357 S**
(45) **Date of Patent:** **** Apr. 2, 2013**

(54) **VIBRATION DAMPER**

(75) Inventors: **Stuart Duane Wright**, Hayden, ID (US); **Becky Lee Wright**, Hayden, ID (US)

(73) Assignee: **Stuart D. Wright**, Hayden, ID (US)

(**) Term: **14 Years**

(21) Appl. No.: **29/395,278**

(22) Filed: **Dec. 29, 2011**

(51) **LOC (9) Cl.** **22-01**

(52) **U.S. Cl.** **D22/107**

(58) **Field of Classification Search** **D22/107, D22/199; 124/88-92; D21/572**
See application file for complete search history.

Primary Examiner — Michael A Pratt

(57) **CLAIM**

The ornamental design for a vibration damper, substantially as shown and described in FIGS. 1-4.

DESCRIPTION

FIG. 1 is an isometric top right view of the new design. FIG. 2 is an isometric bottom right view of the new design. FIG. 3 is a front view of the new design; and, FIG. 4 is a side view of the new design.

Design is symmetrical front and back, top and bottom. Omitted are the back view and opposite side view.
